UNITED STATES PATENT OFFICE.

WALTER M. COLVIN, OF WASHINGTON, DISTRICT OF COLUMBIA, ASSIGNOR OF ONE-FIFTH TO RICHARD B. OWEN, OF WASHINGTON, DISTRICT OF COLUMBIA.

DESIGN FOR A TOY BALLOON-DOLL.

59,718.

Specification for Design.

Patented Nov. 22, 1921.

Application filed June 9, 1921. Serial No. 476,356. Term of patent 14 years.

To all whom it may concern:

Be it known that I, WALTER M. COLVIN, a citizen of the United States, residing at Washington, District of Columbia, have invented a new, original, and ornamental Design for a Toy Balloon-Doll, of which the following is a specification, reference being had to the accompanying drawing, forming part thereof.

Figure 1 is a front elevational view of the doll and

Fig. 2 is a side elevational view of the doll, showing my new design.

I claim:

The ornamental design for a toy balloon doll as shown.

WALTER M. COLVIN.
